UNITED STATES PATENT OFFICE.

ARTEMAS RUSH, OF LEON, ASSIGNOR OF ONE-HALF TO JAMES MORTON,
OF BURLINGTON, IOWA.

SAW-SET.

SPECIFICATION forming part of Letters Patent No. 237,049, dated January 25, 1881.
Application filed April 12, 1880. (No model.)

To all whom it may concern:

Be it known that I, ARTEMAS RUSH, of Leon, in the county of Decatur and State of Iowa, have invented certain new and useful 5 Improvements in Saw-Sets; and I do hereby declare that the following is a full, clear, and exact description of the invention, which will enable others skilled in the art to which it pertains to make and use the same, reference 10 being had to the accompanying drawings, and to the letters of reference marked thereon, which form a part of this specification.

My invention relates to an improvement in saw-sets; and it consists in certain novel devices comprised therein, as the trip-hammer, trigger, and adjustable gage, and in the means employed for operating the hammer automatically, and also in the combination and arrangements of the parts, as hereinafter more 20 fully set forth.

In the drawings, Figure 1 is a side elevation of my device. Fig. 2 is a similar view of the reverse side thereof, and Fig. 3 is a view in perspective.

25 A indicates one of the handles of the device, which extends forward at the point remote from the handle proper, to provide a suitable receptacle for the set-screw *a*, which latter is designed to regulate the position or angle of inclination of the saw by supporting it at the moment when the punch *D* is caused to impinge conjointly upon the saw and anvil *d*.

B represents the under handle or plier, whose extension forms the jaw *g*.

30 The gage *e* is provided with the vertical flange *e'*, and it has a semicircular piece cut therefrom at the point where the punch *D* strikes the anvil *d*. It is also provided with the metallic guide *E*, which is rigidly attached 35 to the longitudinal plate of the gage *e*. In this plate is provided a longitudinal slot, through which the set-screw *f*, Fig. 2, projects, the latter being designed to hold the guide steadfast when adjusted to the tooth of the 40 saw.

45 The trigger *F* is pivoted by means of the screw *a'*, projecting through an orifice provided in the lower part thereof, and caused to oper-

ate by the wire spring *b*, which is rigidly secured to the handle *A* at one end thereof and hooked to the trigger *F* at the other. When the handles are opened the top of the trigger comes beneath the stud or pin *b'*, located in the hammer *G*, and as the handles are closed the trigger is pushed from under said pin by a corresponding pin, *d'*, in the jaw of the handle, as shown.

To the handle or plier *B* is rigidly attached, by the screw *e'*, the longitudinal spring *h*, which projects into the shoulder *h'* of the hammer *G*, as shown.

The hammer is pivoted in the frame *i*, which latter is rigidly secured to the jaw *g*; and when the trigger *F* is sprung by compression of the handles *A* and *B*, at the moment when the punch *D* impinges upon the tooth of the saw, the hammer descends upon the head of the punch and effectually completes the work.

The punch *D* is provided with the spiral spring *g'*, which adjusts it, and also increases the resistance or requisite pressure upon the handles, and hence the pressure upon the tooth; and it is provided with the pin *m*, which works in the vertical guide *n* in the jaw *g*. The guide prevents the punch from turning and holds it in exact position in its descent and pressure upon the tooth, and the hammer strikes the tooth when the pressure is greatest, as aforesaid.

What I claim is—

1. The combination of the handles *A* and *B*, guide *E*, punch *D*, trigger *F*, and hammer *G*, operated by longitudinal spring *h*, substantially as shown and described.

2. The combination of the handles *A* and *B*, trigger *F*, punch *D*, having spring *g'*, hammer *G*, spring *h*, and jaw *g*, having guide *n*, substantially as shown, and for the purpose described.

In testimony that I claim the foregoing as my own I affix my signature in presence of two witnesses.

ARTEMAS RUSH.
